Primary Examiner — Brandon M Rosati*Assistant Examiner* — Lauren D McVey(74) *Attorney, Agent, or Firm* — Seager, Tufte & Wickhem LLP(57) **CLAIM**

The ornamental design for an internet gateway, as shown and described.

DESCRIPTION

FIG. 1 is a front perspective view of an internet gateway, showing our new design;

FIG. 2 is a front elevation view thereof;

FIG. 3 is a left side elevation view thereof;

FIG. 4 is a right side elevation view thereof;

FIG. 5 is a top plan view thereof; and,

FIG. 6 is a bottom plan view thereof.

The evenly spaced broken lines that are immediately adjacent to the claim represent the bounds of the claim, while all other evenly spaced broken lines are directed to environment; the broken lines form no part of the claimed design.

1 Claim, 6 Drawing Sheets(56)
